(57) **CLAIM**

The ornamental design for a toy, as shown and described.

DESCRIPTION

FIG. 1 is a perspective view showing my new design;
FIG. 2 is an end view thereof;
FIG. 3 is a side elevational view thereof, depicted in a
horizontal orientation; and,
FIG. 4 is a side elevational view rotated 45° from the view
of FIG. 3, also shown in a horizontal orientation.
